H. R. SARGENT

WALL ATTACHMENT MEANS FOR ELECTRICAL DEVICES

Filed Feb. 13, 1924

Inventor:
Howard R. Sargent,
by *Alphonse S. Laut.*
His Attorney.

UNITED STATES PATENT OFFICE.

HOWARD R. SARGENT, OF BRIDGEPORT, CONNECTICUT, ASSIGNOR TO GENERAL ELECTRIC COMPANY, A CORPORATION OF NEW YORK.

WALL-ATTACHMENT MEANS FOR ELECTRICAL DEVICES.

Application filed February 13, 1924. Serial No. 692,606.

To all whom it may concern:

Be it known that I, HOWARD R. SARGENT, a citizen of the United States, residing at Bridgeport, in the county of Fairfield, State 5 of Connecticut, have invented certain new and useful Improvements in Wall-Attachment Means for Electrical Devices, of which the following is a specification.

The present invention relates to electric 10 house wiring, and more especially to flush wall receptacles, switches, etc.

Flush wall electric devices are generally installed in sheet steel boxes secured in the wall and the device attached to the front 15 edge thereof by screws passing through attaching lugs on the device and engaging threaded ears on the box. Formerly the attaching lugs were made relatively small and the finish wall plates were hollowed out 20 at the back thereof to fit over the relatively small switch lugs. Much difficulty has always been experienced in getting the switch boxes installed properly to align with the surface of the plaster when completed. It 25 has accordingly been the practice during recent years to provide the electric wall devices with ears having side enlargements or wings so that they may bear against the surface of the plaster and thereby automatically and correctly position the electric device, irrespective of the position of its box.

It has been found, however, that the enlarged attachment lugs are sometimes objectionable, such as the failure of old forms 35 of finish plates to fit thereover, or other nearby devices to interfere therewith.

The object of my invention is to provide an improved electric device attachment ear of the enlarged or winged type that can 40 be converted with facility to the small or old type of lug.

One form of the invention is shown in the accompanying drawing in which Fig. 1 is a front elevation of a wall switch provided 45 with my improved attachment ears and mounted in its wall box, the finish plate being shown broken away; Fig. 2 is a side elevation of the same with the wall and sheet metal finish plate shown in vertical section; Fig. 3 is a perspective view of a switch 50 bridge piece with each end provided with an integral attachment ear with the winged enlargement removed, and Fig. 4 is a view

similar to Fig. 2 with an old form of solid finish plate in place thereon.

The sheet metal switch box 1 shown is provided at each end with a bracket 2 with two counter-sink holes for reception of the screws 3 whereby it is secured to the framework 4 of the house wall, 60 and it also has a threaded ear 5 adapted to be engaged by the screw 6 whereby the switch 7 is attached to the box. This is but an example of well known box constructions.

The wall switch 7 has secured to each end 65 an attachment ear 8 and, as shown in the drawing, the ears are integral with the switch bridge piece 9 to which the switch base 10 is directly attached.

The ears 8 are each provided with an integral winged extension 11 whereby the bearing area presented by the lugs to the plaster surface 12 is greatly enlarged and thereby avoiding any tendency of the plaster to crush when the holding screws 6 are turned 75 home.

The winged extensions 11 are in the shape of round-ended blades, each formed with a side notch 13 extending to about the longitudinal axis thereof, and it is integrally attached to the outer end of the lug 8 at the inner edge of its notch 13. In order that the extension 11 may be, when desired, readily broken off from the lug 8, the metal is weakened by scoring it along a line 14 at or near 85 the point of attachment. By reason of the line of weakening being through or adjacent the center of the winged extension, there will be no tendency for it to bend relative to the lug 8 when the latter is put under 90 tension by the turning up of the attachment screw 6.

The finish plate 15, shown in Figs. 1 and 2, is of the sheet metal type in general use and is adapted to be held to the switch by 95 screws 16 passing through it and engaging tapped holes in the bridge piece 9. Owing to its struck-up formation, the plate has a rear cavity in which the lugs 8 and their extension wings 11 are freely received while 100 the edge 17 of the plate closely engages the surface of the plaster 12.

When a wall switch or other electrical device, provided with the improved lugs, is to be installed with a solid finish plate 15', 105 as shown in Fig. 4, or whenever the winged

extensions 11 would interfere with other parts, they may be removed by bending back and forth about the scored portion 14. The bridge piece with its reduced lugs 8 is shown in Fig. 3.

With the lugs 8 deprived of the winged extensions 11, it is necessary to provide supporting means therefor, since the plastered surface is no longer available for that purpose. Accordingly, I have shown in Fig. 4 nutlocks 18 mounted on the attachment screws 6' and provided with bent-up tips 19 which project through apertures 20 in the lugs as shown and described at length in my 16 Patent No. 1,173,040, February 22, 1918.

While I have shown and described the best embodiment of the invention known to me, I do not desire to be restricted thereto.

What I claim as new and desire to secure 20 by Letters Patent of the United States, is:—

1. The combination with an electrical device having supporting lugs projecting beyond its ends for use in mounting it in an outlet box, of integral extensions on said 25 lugs adapted to engage the surface of a wall when the device is mounted in an outlet box in the wall, the line of connection between the lugs and extensions being weakened whereby the extensions may be severed readily from the lugs.

2. An electrical wiring device having projecting lugs at its ends, said lugs being provided with openings for use in mounting the device in an outlet box, and readily removable wall-engaging extensions carried by 35 said lugs beyond said openings.

3. Means for use in mounting an electrical device in an outlet box, including an attachment lug provided with an opening to 40 receive fastening means for use in attaching the lug to an outlet box, and a readily removable wall-engaging extension carried by said lug beyond said opening.

4. An attachment lug for electrical devices for use in mounting an electrical device in an outlet box, said lug having an opening to receive a fastening means for attaching it to an outlet box and being provided at one side of said opening with means for use in attaching it to an electrical device, and at the other side of said opening with readily removable wall-engaging means.

5. Means for use in mounting an electrical device in an outlet box, including an attachment lug having an opening to receive a fastening means for attaching it to a box, and a winged extension integrally united thereto, the line of connection between the extension and the lug being weakened whereby the extension may be broken off readily to leave the lug portion with the opening for the fastening means.

6. A bridge piece for electrical devices, the ends of which form lugs provided with 65 openings adapted to be used when attaching the bridge piece to an outlet box, and removable wall-engaging means carried by said lugs beyond said openings.

7. A bridge piece for electrical devices, 70 the ends of which form lugs provided with openings adapted to be used when attaching the bridge piece to an outlet box, and readily removable wall-engaging extensions carried by said lugs beyond said openings.

8. A bridge piece for electrical devices, the ends of which form lugs provided with 75 openings adapted for use in attaching the bridge piece to an outlet box, and winged extensions connected to said lugs, the line of connection between the lugs and extensions being relatively weak whereby the extensions may be severed readily from the lugs.

In witness whereof, I have hereunto set my hand this 11th day of February 1924.

HOWARD R. SARGENT.
